(57) **CLAIM**

The ornamental design for an automatic external defibrillator training device, as shown and described.

DESCRIPTION

FIG. 1 is a top perspective of an automatic external defibrillator training device showing our new design;

FIG. 2 is a bottom perspective view thereof;

FIG. 3 is a side view thereof;

FIG. 4 is a front end view thereof;

FIG. 5 is a rear end view thereof;

FIG. 6 is a top view thereof; and,

FIG. 7 is a bottom view thereof.

The broken lines in the drawings are included for the purpose of illustrating portions of the defibrillator that form no part of the claimed design.
